UNITED STATES PATENT OFFICE

WILLIAM S. EDSALL, OF BROOKLINE, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

CIRCUIT INTERRUPTION

Application filed February 17, 1930. Serial No. 428,894.

This invention relates to circuit interrupters and to methods and apparatus for extinguishing circuit interrupting arcs.

It has been proposed to extinguish electric arcs by drawing a submerged arc in an arc extinguishing body, as a body of oil, or a mass of gravel, or by playing a heavy solid stream of an arc extinguishing fluid, usually a liquid, against the arc. In all of these instances, however, the arc maintains its integrity in that it merely forms a hole in the submerging body, or dodges the fluid stream and maintains itself just beyond the border of the stream. Thus, while the arc extinguishing medium has some action on the arc, the medium is in no manner fully effective.

I have discovered that, if the arc-extinguishing medium is presented to the arc in isolated particles the size of which is small compared to the thickness of the arc, they can be brought into intimate contact with the arc without diverting the arc sensibly away from them, and thus can exercise their utmost effect in extinguishing the arc. This constitutes one of the objects of the invention.

A further object of the invention is to force such a quantity of small discrete and dispersed arc extinguishing particles into and through the arc, as to cause the arc to be extinguished and its restoration prevented. Preferably the particles are hurled forcibly into and through the arc as a spray, wherein the particles travel with considerable speed and momentum and are dispersed within the spray, that is, each particle is separated from all others, so that they can penetrate the arc independently in different places without causing the arc to be diverted away from them. This constitutes a further object of the invention.

The amount of the particles thrown into the arc is intended to be such as to cool and extinguish it, and the extinguishing action of the particles may be supplemented by the attenuation of the arc, by separating the arcing members of the switch.

A further object of the invention is to extinguish the circuit interrupting arc by forcibly hurling into and through the arc,

and the zone thereof, and against the supporting surfaces between which the arc plays, small, cold, discrete, and dispersed, solid, particles of an arc-extinguishing material which preferably is electrically insulating, and is physically unchanging, at least for so long as it remains in effective contact with the arc, whereby to cool the arc and the arcing surfaces, and thus extinguish the arc. Sand is a highly suitable material and the use of sand for this purpose constitutes another object of the invention.

The electric arc consists of electrically charged ions, which are mainly negatively charged, and which act as carriers for the circuit current in the arc zone. If the electrified ions are absent from the arc zone, there can be no arc.

It is an object of the present invention to capture these ions by introducing into the arc zone moving particles having electric charges of such polarity as to nullify the charges of the ions in the arc zone, and thereby to destroy the conductivity of the arc zone and restore the dielectric strength thereof. Since the ions in the arc zone are mainly negatively charged, the electrified ion-capturing particles will be mainly positively charged. When the arc is formed by alternating current, and thus momentarily ceases at each zero point of the alternating current wave, the introduction of charged particles will take place at such time, whereby to remove the conducting ions from the arc zone at the time of reduced formation of ions, thereby to facilitate the work of restoring the dielectric strength of the normally insulating medium in which the usual arc is formed. This is a further object of the invention.

Another object of the invention is to electrify the discrete arc-extinguishing particles above mentioned and inject them forcibly into and through the arc and against the faces of the arc-supporting members, whereby not only to cool the arc and thereby render it nonconducting but also electrically to capture the conducting ions in the arc zone

and also at the main zones of origin of the ions.

A yet further object is generally to improve methods and apparatus for circuit interruption.

Fig. 1 diagrammatically illustrates a circuit interrupting and arc-extinguishing apparatus embodying certain of the features of the present invention.

10 Fig. 2 is an end view of the nozzle of Fig. 1.

Fig. 3 is a view generally similar to Fig. 1 but illustrating a modified form of apparatus for introducing electrically charged particles into the arc.

15 Fig. 4 is a section along line 4—4 of Fig. 3.

Fig. 5 is a view generally similar to Fig. 3, but wherein the air stream is removed from 20 the blast of solid particles prior to their introduction into the arc.

Fig. 6 is a perspective view of the separating and electric charging member of Fig. 5.

25 Fig. 7 is a diagrammatic view of a modified system, wherein electrified liquid particles are discharged into the arc zone.

Fig. 8 is a diagrammatic illustration of a further modified form of the invention, wherein the arc-extinguishing particles pass 30 into and through the arc zone mainly by gravity.

Fig. 9 is a diagrammatic illustration of another form of the invention wherein the arc extinguishing particles are brought into 35 the arc by movement lengthwise of the arc.

As shown in Fig. 1, the circuit interrupter includes the stationary contact or arcing member 10 and the cooperating movable contact or arcing member 12. The arcing member 12 is movable into and out of engagement with the stationary arcing member by any suitable operating mechanism which, as here shown, includes the pivoted lever 14, which lever is latched releasably 45 in the engaged condition of the contacts by a latch 16 that releasably engages a latch pin 18 of the lever. The latch is adapted to be released from holding engagement with the pin by an electro-magnet 20 upon overload 50 or other abnormal condition of the circuit including conductors 22 and 24 which are connected with the contact members of the switch, whereby to effect the opening of the switch. The electromagnet may be energized by means of a relay 26 from a source 55 of power 28. The relay can be operated by a current transformer 30 included in the conductor 22 and adapted to close its contact upon overload in said conductor.

60 When the contact members 10 and 12 are separated under load, an arc is established between them. In accordance with one of the features of this invention, means are provided to extinguish the arc by forcing into 65 and through the arc cold, discrete particles

of material which act to cool the arc and thus to cause it to become extinguished. To this end, the contact members 10 and 12 are separable within or in the path of material discharged through a nozzle 31 which, preferably, is formed of insulating material and is small at the inlet end 32 and large at the outlet end 34 and tapers uniformly between the inlet and outlet. A pipe T 36 is connected with the inlet 32 of the corresponding nozzle and has a pipe 38 connected therewith which extends to an electrically-controlled valve 40. A pipe 42 is connected with said valve and extends to a tank 44 containing a supply of air, carbon dioxide, nitrogen or the like, gaseous fluid at elevated pressure. A supply of discrete particles of arc extinguishing material 46 is maintained in an elevated hopper or receptacle 48 which preferably is pressure tight and has its top opening closed and sealed by the removable cover 49. A pipe 50 extends from the bottom of the hopper into the T 36 so that a pile 52 of the material is formed and maintained in the passage of the T. A manually controlled valve 53 is interposed between the ends of said pipe 50 and constitutes means for regulating the amount of the material discharged into the arc zone. A pipe 54 communicates with the pipe 38 and the interior of the hopper above the material therein, and between said hopper and the valve 40, so that when fluid pressure is admitted to said pipe 38, it is also admitted to the top of said hopper whereby to cause the material to flow positively into the T and mingle with the fluid flowing therethrough.

The flow of fluid is controlled by a solenoid 56 which is energized by the operation of the relay 26 to open the valve 40 and admit fluid to flow through the T and the nozzle. A dash pot 58 preferably is associated with the valve 40 so as to delay the closing of the valve for a considerable period after the contact members have 110 separated.

As thus arranged, when the switch is opened upon overload and contact members 10 and 12 are separated and an arc is drawn therebetween, the valve 40 also is opened by the solenoid 56 and fluid is caused to flow rapidly through the T 36 and into and through the expanding nozzle 31. During its passage through the T, it picks up particles of the material 46 which are therein and which are constantly flowing into the fluid stream for so long as the stream maintains its flow, and thereby hurls the particles into and through the arc, the particles being dispersed throughout the gas blast. The particles are or can be at room temperature and thus are cold with respect to the arc and so cool the arc and quench it. If the arc is an alternating current arc, the flow of the particles is adapted to continue be- 125 130 135

yond the period of the zero point of the current wave so that the particles act upon the hot medium between the contact members and cool it at the time there is little potential on the contact members, whereby to restore the dielectric strength of the medium before full voltage is restored to the contact members so that the voltage cannot break down the medium. The contact members 10 meanwhile are moving in a circuit opening direction and thereby increasing the distance between them, whereby to assist the arc extinguishing action of the particles by attenuating the arc. I prefer to use sand as 15 the arc quenching material since sand is an insulator, is noncombustible, and is not physically altered by the arc for the time it is present therein. Other material can be employed, however. Small conducting particles 20 can be used with discretion, in certain instances, especially where their speed through the arc is so great that they do not become heated sufficiently to give off conducting ions. An insulating material is 25 much to be preferred, however, over a conducting material. The speed of material through the arc preferably is relatively high so as to drive a large amount of cooling particles so rapidly into and through the 30 arc that they are not heated to an ion-emitting temperature therein.

In the modified form of the apparatus illustrated in Fig. 3, I have illustrated means for discharging electrically charged particles into and through the arc, the particles having a charge the polarity of which is opposite that of the charge of the conducting ions in the arc, whereby to capture said particles and nullify the charges thereof and 40 render the arc space non-conducting. To this end, I provide the insulating nozzle 31 with an intermediate conducting section 60 which is spaced from the electrically conducting T 36 by an insulating portion of the 45 nozzle. Said conducting section 60 is provided with a plurality of conducting guide vanes 62 which are extended generally lengthwise of the nozzle. A source of high 50 continuous electric tension 64 is connected with the conducting section 60 and the vanes 62 and thereby maintains them at a suitably high tension which preferably is positive since the conducting ions of the arc are for the most part negatively charged. The 55 discrete and dispersed particles of arc extinguishing material 46, as they are blown through the nozzle by a blast of fluid from the pressure tank 44, are caused individually to impinge against the conducting section 60 and the vanes and thereby to acquire electric 60 charges having the polarity of the conducting section. The charged particles are further impelled into the arc zone and capture the oppositely charged conducting ions 65 therein and nullify the charges and thereby

cause the arc zone to become non-conducting whereupon the arc ceases. If the arc is an alternating current arc, the flow of the charged particles is maintained at least throughout one current zero and preferably 70 for a number of current zeros so that the residual ions in the arc zone existing at the time the arc current is zero and the arc is momentarily out are rendered non-conducting whereby to restore the dielectric strength 75 of the normally insulating medium between the contact members and prevent the re-establishment of the arc when potential is again built up at the contact members.

The ionized particles also travel over the 80 arcing faces of the contact members, which are the main sources of origin of the ions, and impinge thereagainst whereby to cool the surfaces and capture the ions at their sources. The blast of gaseous fluid which 85 carries the arc extinguishing particles also assists in attenuating and extinguishing the arc.

Fig. 5 illustrates the principle of the apparatus of Fig. 3 except that the blast of 90 discrete, solid particles, at the time the particles pass into the arc, is free from the gas stream which in Fig. 3 carries them. In Fig. 5 the nozzle 70 discharges into the arc zone between the arcing members 10 and 12 95 contained in a closed chamber 72. The conducting section 74 of the insulating nozzle is provided with a plurality of plates or vanes 76, see especially Fig. 6, adjacent pairs of which vanes are connected together 100 at their front or entering edges 78. The vanes thus provide passages 80 through which the solid particles and gas are free to pass. The spaces 82 between the pairs of connected plates are in communication with a chamber 84 which is connected by a pipe 86 formed preferably of insulating material or having an insulating section. Said pipe is connected with a suction device 88 which 105 may be a centrifugal exhauster operated by the electric motor 90. Thus, when the exhauster is operated, air is withdrawn from the chamber 72 so that a blast of air is caused to enter into the open end 92 of the T 36a and pick up the arc extinguishing material therein and so carry the material through the nozzle. The air passing 110 through the passages 80 is caused to curl around the edges of the plates 76 that confront the arc and thus to enter the passages 82 and to pass into the exhauster. The particles of solid material, however, have such momentum that they can not follow the air stream and consequently continue to move rapidly with little change of direction into 115 and through the arc zone. The conducting section 74 and the plates 76 are connected to a suitable source of continuous high tension 64 as in the previous modifications so that the arc extinguishing particles become 120 125 130

charged prior to their entrance into the arc zone. The charged particles thus act to capture the conducting ions in the arc zone and thereby render the arc zone nonconducting in the manner heretofore explained.

Because of the absence of the gas blast in the arrangement illustrated in Fig. 5, the arc is not displaced and is caused to become extinguished by the action of the spray of arc extinguishing particles alone.

Under certain conditions, the arc extinguishing material can be a liquid which is capable of passing into and through the arc without being ignited or without decomposing in any deleterious manner when the liquid is discharged as a spray of discrete dispersed particles into and through the arc and against the seats of the arc on the contact members.

Fig. 7 illustrates an apparatus for discharging such a liquid spray. A spray nozzle 100 has an orifice 102 directed to discharge a spray of fluid into the arc zone between the separated contact members of the circuit interrupter. The characteristics of the spray of atomized liquid are controlled by the adjustable valve member 104. The liquid passage 106 in the valve casing is connected through a pipe 107, which can be of insulating material, and an electrically controlled valve 108 with a receptacle 110 containing a supply of the liquid under pressure. The liquid can be carbon tetrachloride, pure water and the like. The operation of the spray is controlled as heretofore by the solenoid 112 which opens the valve 108 coincidently with the separation of the contact members of the interrupter on overload. The closing of the valve is delayed by a dash pot 114. The spray of dispersed liquid particles passes through the arc and thereby cools it and renders the arc zone non-conducting. The liquid particles can be electrically charged by being impelled through a charging ring 116 which is maintained at a suitably high continuous potential by the source of potential 64. The other terminal of said source can be connected with the valve casing 100. The liquid particles issuing forcibly from the nozzle 100 and passing through the charging rig 116 become electrically charged and thus when in the arc zone capture the conducting ions and render them non-conducting essentially in the manner previously set forth.

In the modification illustrated in Fig. 8, the force of gravity is substituted for the air blast to carry the arc-extinguishing particles into the arc zone.

A supply 46 of the particles, as sand, is contained in a suitable container 48a which is elevated above the separable contact members or electrodes 10 and 12 and discharges a stream or blast of sand from the bottom

of the container through the fan-shaped nozzle 118, which blast falls by gravity into the arc zone between the separated electrodes. The discharge of sand is controlled by a valve 53a the operation of which is effected by a solenoid 56a under the control of the overload relay 26. The weight of the sand and gravity closes the valve after the arc has been interrupted and the relay 26 de-energized. The falling sand is electrically charged, prior to its entrance into the arc zone, by passing through the metal screen 62a which is energized at a positive potential by the voltage source 64, at least for so long as an arc persists. The action of the apparatus is essentially as has been described heretofore.

In the further modification illustrated in Fig. 9, the arc-extinguishing particles are moved in the direction of the length of the arc. The circuit interrupting arc between the contact members 10 and 12 takes place in the preferably insulating tube 31a along the length of which the sand blast is directed by the air blast in the manner heretofore described. The arc is drawn coaxially of the tube and the sand and air blasts pass longitudinally of the arc and both are caused to be closely confined in the arc stream by the closely surrounding tube. Conical baffles 120 are disposed within the tube at spaced intervals to direct the sand and air positively into the arc so as to render the blast more effective. The sand blast is electrified by passing through the electrified screen 122 which is disposed between the outlet of the hopper 48 and the entrance to the tube 31a. The screen is maintained at a suitably elevated and preferably positive potential by the high potential source 64. The structure and operation of the various elements is substantially as has been described above.

I claim:

1. An electric circuit interrupter having arc-supporting members, means to extinguish an electric arc formed between said members including pneumatic means providing a gas blast for forcibly impelling discrete dispersed arc-extinguishing particles into the arc in such quantity as to effect the extinguishing of the arc and means to separate said particles from the gas blast prior to entering the arc.

2. An electric circuit interrupter having arc-supporting members and means to discharge discrete and dispersed particles of an arc-extinguishing material into the arc zone between said members so as to penetrate the gases of a circuit interrupting arc drawn therebetween, which particles carry electric charges having a polarity opposite that of the major current-carrying ions of the arc and of sufficient intensity to neutralize the charges carried by said ions.

3. An electric circuit interrupter having arc-supporting members, and means to introduce into the arc zone between said members, an electrically charged medium which 5 de-ionizes the current-carrying medium in said arc zone and renders it non-conducting.
4. An electric circuit interrupter having arc-supporting members, and means to de-ionize the ionized medium of the arc zone 10 between said members including means to introduce an electrified de-ionizing medium into said ionized medium.
5. An electric circuit interrupter having arc-supporting members between which an 15 ionized atmosphere exists at the time an arc is present between said members, and means to de-ionize said ionized atmosphere including means to introduce electrically charged de-ionizing particles into said ionized atmosphere, the amount and sign of the charges 20 of which are sufficient to deionize said atmosphere.
6. An electric circuit interrupter having arc-supporting members between which negatively charged ions exist when an arc is 25 formed therebetween and means to neutralize the conductive effect of said ions including means to introduce into the arc zone between said members particles having electric 30 charges which are opposite to and sufficient to neutralize the charges of said ions.
7. An electric circuit interrupter having arc-supporting members between which negatively charged ions exist when an arc is 35 formed therebetween and means to neutralize the conductive effect of said ions including means to introduce into the arc zone between said members electrically charged carriers having charges the amount and sign 40 of which is sufficient to neutralize the charges of and capture said ions.
8. An electric circuit interrupter having arc-supporting members and means to capture the conducting ions of and thereby to 45 extinguish the arc including means to direct into the arc zone, between said members, moving carriers of electric charges which capture sufficient quantities of the arc ions to extinguish the arc.
- 50 9. An electric circuit interrupter having arc-supporting members and means to capture the conducting ions of and thereby to extinguish the arc including means to direct into the arc zone between said members moving 55 carriers of electric charges having a polarity which is opposite that of the ions, and having charges the amount of which is equal to the charges of said ions, whereby the ions are attracted to said carriers and 60 are rendered inert.
10. An electric circuit interrupter having arc-supporting members between which an arc can form, and means to extinguish the arc including means to introduce electrical- 65 ly charged particles into the arc, said par-
- ticles having electric charges of such capacity and sign as to destroy the conductivity of the arc medium.
11. An electric circuit interrupter having separated arc supporting members between which an electric arc can form and means to extinguish the arc including means to introduce electrically charged particles into the arc in sufficient amount to extinguish the arc. 70
12. A circuit interrupter having separated arc-supporting members between which an arc can form, and means to extinguish the arc including means to introduce into the arc solid discrete particles of arc extinguishing material which are electrically charged, the volume of said material and the amount and sign of the charges of the particles being sufficient to destroy the conducting property of the arc medium. 75
13. An electric circuit interrupter having arc-supporting members, means to extinguish the arc between said members including means to impel discrete particles of arc extinguishing material into the arc, and means to charge said particles electrically prior to their introduction into the arc. 80
14. An electric circuit interrupter having arc-supporting members, means to extinguish, the arc between said members including an electrically charged member, and means to pass discrete particles of arc-extinguishing material into engagement with said electrically charged member and thence into the arc. 85
15. An electric circuit interrupter having arc-supporting members, and means to extinguish an arc between said members including an electrically charged member, and pneumatic means to impel a quantity of discrete arc-extinguishing particles into engagement with said electrically charged member to become electrically charged thereby, and thence to pass said charged particles into the arc zone between said arc supporting members. 90
16. The method of extinguishing a circuit interrupting arc which consists in introducing into the arc rapidly moving free carriers of electric charges having a polarity opposite that of the current-carrying ions in the arc zone, whereby said carriers are caused to capture said ions and thereby extinguish the arc. 95
17. The method of extinguishing an electric arc which consists in neutralizing electrically charged ions in the arc by oppositely electrically charged free discrete particles. 100
18. The method of extinguishing an electric arc consisting of electrically charged particles which consists in capturing said particles by introducing into the arc rapidly moving discrete particles which are oppositely electrically charged. 105
19. The method of extinguishing an electric arc which consists in neutralizing electrically charged ions in the arc by oppositely electrically charged free discrete particles. 110
20. The method of extinguishing an electric arc consisting of electrically charged particles which consists in capturing said particles by introducing into the arc rapidly moving discrete particles which are oppositely electrically charged. 115
21. The method of extinguishing an electric arc which consists in neutralizing electrically charged ions in the arc by oppositely electrically charged free discrete particles. 120
22. The method of extinguishing an electric arc consisting of electrically charged particles which consists in capturing said particles by introducing into the arc rapidly moving discrete particles which are oppositely electrically charged. 125
23. The method of extinguishing an electric arc which consists in neutralizing electrically charged ions in the arc by oppositely electrically charged free discrete particles. 130

19. The method of extinguishing an electric arc which consists in discharging into the arc an arc-extinguishing medium in the form of a spray of discrete dispersed particles which carry electric charges the polarity of which is opposite that of the current-carrying ions of the arc.
20. A circuit interrupter having electrodes which support an electric arc, including a gas blast means to direct an arc-extinguishing medium into the arc, and means to remove the medium from the blast prior to the arc, said medium being in the form of dispersed particles which are so small compared with the thickness of the arc and being free from the gas blast which impels them so that they can penetrate the arc without diverting the arc away from them and can act efficiently on the arc to de-ionize it.
21. An electric circuit interrupter having arc-supporting members, means to direct a stream of discrete arc-extinguishing particles into the arc in the direction of the length of the arc, and means to electrically charge said particles prior to their entrance into the arc.
22. An electric circuit interrupter having arc-supporting members, means to direct a combined blast of a fluid and discrete arc-extinguishing particles into the arc in the direction of the length of the arc, and means to electrically charge said discrete particles prior to their entrance into the arc.

In testimony whereof, I have signed my name to this specification.

WILLIAM S. EDSALL.
